HAT STAY

Alice May Olson and Ober Henry Olson,
Madison, Wis.

Application June 7, 1948, Serial No. 31,574

4 Claims. (Cl. 132—62)

1

This invention relates to a hat stay for holding a hat on the head of the wearer and constitutes a continuation in part of application Serial No. 739,526 filed April 5, 1947, now Patent No. 2,517,228.

One object of the invention is to provide a simplified hat stay or fastener for retaining a hat on the head of the wearer.

Another object is to provide a hat stay which will remain securely in place when fastened in the hair of the wearer to whom the hat is secured.

Another object is to provide a hat stay the parts of which are substantially concealed when in place.

Another object is to provide a hat stay of less costly parts and which may be readily applied to and removed from a hat.

These and other objects of the invention will appear hereinafter in connection with the description of an embodiment of the invention illustrated in the accompanying drawing.

In the drawing:

Figure 1 is a side elevational view showing the parts of the hat stay;

Fig. 2 is a side elevational view of the fastener opposite from the side shown in Fig. 1;

Fig. 3 is a perspective view showing the hat stay in place within a hat;

Fig. 4 is a detail section showing the fastener engaged in the hair of the wearer;

Fig. 5 is a section through the ears of the toothed clip taken on line 5—5 of Figure 1;

Fig. 6 is a front elevational view of the spring plate of the assembly; and

Fig. 7 is an enlarged section taken on line 7—7 of Fig. 6.

The drawing shows a hat stay or fastener comprising a generally flat pin 1 for insertion through the crown of hat 2. The outer end of the pin is ground to receive a small bead or head 3 which is substantially permanently secured thereto and the inner end 4 of the pin is sharpened to a point for ready insertion of the pin through the crown of a hat without injury to the hat.

The spring plate 5 of generally rectangular shape is secured inside the crown of hat 2 to receive pin 1 when the latter is inserted through the hat crown. The spring plate 5 has holes on opposite ends for sewing or otherwise securing the plate 5 inside hat 2.

The generally rectangular shaped tongue or spring 6 is struck out centrally of the face of spring plate 5 and is integral therewith at one end with the other end free to move relative to

2

the plate. A groove 7 extends transversely of the plate side member centrally of spring 6. The center of spring 6 is grooved transversely complementary to groove 7 and the width and depth of the space provided by said grooves between spring 6 and the side members corresponds to the dimensions of the flat body of pin 1 for ready insertion of the pin between the spring and plate. When in place the inner end portion of spring 1 is confined between the side members of plate 5 and the spring 6 thereof.

Spring 6 biases pin 1 against rotation when either side of the pin is in flat engagement with the plate side members in either of the two positions to which the pin may be rotated.

The remainder of the hat stay comprises a clip 8 formed of a series of curved spaced teeth 9 adapted to engage the hair of the wearer and which project outwardly from the longitudinal body section of clip 8.

The ears 10 are struck out from each end of the body section of clip 8 and a slot 11 is provided at each corner of the clip between the ear and body thereof and extends into the body of clip 8 a slight distance. The slots 11 are longitudinally aligned with each other to receive the flat pin 1. Slots 11 extend outwardly into each ear 10 a distance slightly less than the thickness of pin 1 so that when pin 1 is slipped longitudinally through slots 11 the pin is sprung centrally away from the body of clip 8 to securely hold or bind the pin and clip 8 together. The binding of the pin and clip together is illustrated in Fig. 5 by the slight clearance between the pin and clip centrally of clip 8. Clip 8 engages pin 1 between the spring plate 5 and the portion of the crown of the hat through which pin 1 is inserted. The slots 11 are formed complementary to flat pin 1 so that the pin cannot be rotated without rotating clip 8.

When pin 1 is projected through clip 8, the pin cannot fall out of the hat or loosen up in service as it is securely held in place against removal from the hat by the biasing action thereon of ears 10 of clip 8.

In assembling the hat stay, spring plate 5 is first secured inside the crown of hat 2. While holding the clip 8 inside the hat, pin 1 is then inserted through the crown of the hat, thence through slots 11 of the clip 8 springing ears 10 slightly outwardly of the clip, and thence beneath spring 6 of the spring plate 5. Pin 1 can be inserted through clip 8 only to the shoulder formed where the flat body of the pin becomes round. This spaces clip 8 from head 3 of the pin.

Thereafter by grasping head 3 the wearer can rotate pin 1 to rotate the clip 8 to engage her hair with the curved teeth 9 of the clip and secure hat 2 in place.

The free clip 8 holds pin 1 securely in place against removal except when it is withdrawn by the wearer. The construction of the spring plate permits ready insertion of pin 1 therethrough. The hat stay holds the hat in place when the clip is rotated into engagement with the hair of the wearer and is concealed except for the head 3 which is formed of a pearl bead or other ornamental object. The stay is readily removable for use in other hats.

Various embodiments of the invention may be employed within the scope of the accompanying claims.

We claim:

1. The combination with a hat of a hat stay for holding said hat on the head of a wearer, which comprises a flat elongated rotatable pin sharpened at one end for insertion through said hat and having an integral head at the other end disposed on the outside of the hat for manipulation of said pin, spring means secured inside the hat on a side thereof disposed on the longitudinal side of the head of the wearer and receiving the sharpened end of the flat body of the pin transversely thereof and selectively biasing the pin into either one of two fixed positions to which the pin is disposed to be rotated, and a set of integrally interconnected outwardly curved teeth spaced from each other and removably carried by said pin inside the hat to be rotated by the pin into engagement with the hair of the wearer to hold the hat in place and prevent dislodgment of the pin from the hat of the wearer.

2. The combination with a hat of a hat stay for holding a hat on the head of a wearer, which comprises a flat elongated rotatable pin sharpened at one end for insertion through said hat and having a head at the other end adapted to be disposed on the outside of the hat, spring means secured inside the hat and receiving the inner sharpened end portion of the pin and biasing the pin selectively into either one of two fixed positions to which the pin is disposed to be rotated, and a clip assembled on said pin inside said hat between the spring means and the line of insertion of the pin through the hat, said clip having at least one ear with a slot extending outwardly therein a distance slightly less than the width of the pin and receiving the pin and effecting binding of the pin and clip together upon insertion of the pin through said ear by the pin springing centrally thereof away from the body of the clip, and a series of spaced, curved teeth extending radially from the body of the clip and adapted to engage the hair of the wearer upon rotation of the pin to hold the hat on the head of the wearer.

3. The combination with a hat of a hat stay for holding said hat on the head of a wearer,

which comprises a flat elongated rotatable pin sharpened at one end for insertion through the hat and having a head at the other end adapted to be disposed on the outside of the hat for manipulation of said pin, spring means inside the hat receiving the inner sharpened end portion of the pin and biasing the pin selectively into either one of two fixed positions to which the pin is disposed to be rotated, a separate clip member located inside said hat and receiving said pin, said clip member having a pair of longitudinally spaced ears struck outwardly thereof and slotted inwardly toward the body of the clip to the shape of the pin with the slots extending outwardly in the ears a distance slightly less than the thickness of the pin tending to spring the pin centrally away from the body of the clip when the pin is inserted through the ears to bind the clip and pin together for rotation of the clip when the pin is rotated, and to prevent dislodgment of the pin from the hat, and a series of spaced, curved teeth extending radially from the body of the clip into engagement with the hair of the wearer upon rotation of the pin to hold the hat on the head of the wearer.

4. The combination with a hat of a hat stay for said hat which comprises a flat rotatable elongated pin sharpened at one end for insertion through said hat to dispose the sharpened end inside hat and having a head at the other end disposed on the outside of the hat for manipulation of said pin, a flat plate secured inside said hat with a spring tongue struck outwardly from the face thereof and grooved centrally across the same the width of the pin, a groove complementary to the spring tongue groove extending transversely across the face of the plate to provide a space between the spring tongue and face receiving the flat body of said pin and confining the same selectively in either one of two fixed positions to which the pin is disposed to be rotated, and a set of outwardly curved teeth spaced from each other and removably carried by said pin inside the hat to be rotated by the pin into engagement with the hair of the wearer and hold the hat in place against dislodgment of the pin from said hat.
